ELASTIC BANDS HAVING PIVOTALLY CONNECTED LINKS AND CLEARANCE OPENINGS FOR THE BIASING SPRING

Charles H. Dolansky, 2875 Hochelaga St.,
Montreal 24, Quebec, Canada

Filed Nov. 19, 1956, Ser. No. 622,876

6 Claims. (Cl. 59—79)

The invention relates to elastic bands, and particularly to bands intended to be used with wrist watches.

The primary object of the invention is to provide a band of simple and inexpensive construction which is capable of considerably greater expansion than is normally possible, so as to permit the band to be easily slipped over the hand of the wearer.

Another object of the invention is to provide such a band which can be readily shortened if it is too long, without the use of special tools and by relatively unskilled persons.

A further object of the invention is to provide a band which has smooth edges, so that it will neither scratch the wrist or hand of the wearer nor cause wear on sleeve cuffs or pockets.

Further objects and advantages of the invention will appear more fully from the following description, especially when taken in conjunction with the accompanying drawings which form a part thereof.

In the drawings:

Fig. 1 shows in top plan view a portion of a band embodying my invention;

Fig. 2 is a cross-section on the line 2—2 of Fig. 1, showing the parts in contracted position;

Fig. 3 is a similar view with the parts in expanded position;

Fig. 4 is a view looking outwardly of the inside of one of the front links;

Fig. 5 is a similar view of one of the front links;

Figs. 6 and 7 show the blanks from which the front and rear links, respectively, are formed; and

Fig. 8 shows the band in side elevation.

This invention represents an improvement on the band disclosed in my application S.N. 559,843, filed January 18, 1956, now Patent No. 2,799,135.

The band is composed of front links 2 and rear links 4, arranged in staggered relation with one another. The front and rear links are of the same cross-section and of substantially equal length. Each front link has an outer wall 6, side walls 8 and inwardly turned flanges 10 at the free edges of the side walls. The flanges have notches 12 cut out at each end, and central notches 14 which extend into the side walls 8.

Each rear link has an outer wall 16, side walls 18 and inwardly turned flanges 20. The ends of the flanges have notches 22 which extend into the side walls 18.

Each link of one row is connected to two links of the other row by U-shaped connecting members formed from flat spring wire and having legs 24, 26 extending into the ends of the front and rear links, respectively, and engaging the inner faces of the outer walls, and a crosspiece having portions 28, 30 of different height, the higher portion 28 overlying the front link. Arranged in the front link is a spring formed of a strip of resilient metal and having a central bowed portion 32 engaging the inside of flanges 10, an outwardly bent portion 34 engaging connecting member leg 24 and press-

2

ing it against wall 6, and an inwardly bent end portion 36 extending almost up to connecting part 28. Part 36, as shown in Fig. 4, is narrower than the body of the spring, and is smaller in width than the space between the edges of notches 12.

In the rear link is a flat spring slightly shorter than the spring in the front link and having a central bowed portion 38, outwardly bent portions 40 engaging legs 26, and an inwardly bent end portion 42.

10 The rear links have on their outer walls extensions 44 which are bent down to overlie parts 30 of the connecting members and to be substantially flush with parts 28. These extensions hold the connecting members in the bracelet and thus keep the bracelet assembled.

15 With such an arrangement, the parts are normally in the position shown in Figs. 1 and 2. If a tension is applied to the band, the connecting members rock against the resiliency of springs 34, 40 and the bracelet can expand, the parts then assuming the position shown in 20 Fig. 3. When the tension is released, the springs restore the parts to the normal, retracted position.

In such a structure, the inwardly bent spring ends serve to prevent any substantial longitudinal shifting of the springs while allowing the outwardly bent parts

25 to engage the legs of the connecting member at points well inside the ends of the links, which is necessary for proper operation. At the same time, because of notches 12, 22, the ends of the springs can pass out of the links when the bracelet is expanded, so that the spring parts 34, 40 can be pushed substantially flush against flanges 10, 20, allowing legs 24, 26 to rock through a greater angle and thereby permitting greater expansion of the bracelet.

30 Since parts 28 of the links partially overlie the end edges of flanges 10, any shifting of the front and rear links longitudinally with respect to one another is prevented. On the other hand, notches 22 prevent the creation of a clamping action on the connecting member part 30 between extension 44 and the upper edges of flanges 20, which might otherwise result if part 44 were bent down too tight. At the same time, the use of a full width spring in the rear links is desirable in order to stabilize the motion of the parts and to ensure smooth, even movement during expansion and contraction of the band.

35 The front link is provided with a decorative cap or cover 46 having its side walls 48 bent around side walls 8 and having tabs 50 bent into notches 14 to hold the covers in place. These covers serve to space the rear

50 links slightly apart so as to prevent the hairs on the wearer's wrist from being caught between them. The ends of covers 46 are swaged over the ends of front walls 6, as at 52, so as to provide a smooth edge along the ends of the front links. The bending over of extensions 44 provides a smooth edge along the ends of the rear links.

55 While I have described herein one embodiment of my invention, I wish it to be understood that I do not intend to limit myself thereby except within the scope of the claims hereto or hereinafter appended.

I claim:

1. An expandible band having two rows of links arranged in parallel staggered relation, each link having an outer wall, side walls connected thereto, and inwardly turned parts at the free edges of the side walls extending at least partly across the space therebetween, U-shaped connecting members having legs of greater width than thickness extending into said links and engaging the inner faces of the outer walls and a part connecting said legs, and flat springs in said links having central portions engaging the inner faces of said inwardly

turned parts, outwardly bent portions engaging said legs at points spaced from the ends of the links and pressing the legs against the outer walls, and inwardly bent end portions, said inwardly turned parts having recesses there-in opposite said end portions of a width at least equal to the width of the end portions, whereby when said band is expanded said spring end portions can move out through said recess and said legs can press the outwardly bent spring portions against the inwardly turned parts, so as to permit full expansion of the band, the recesses of the links of a first row being of less width than the inwardly turned parts, whereby said connecting parts partially overlie the end edges of the inwardly turned parts, the end portions of the springs in such first row being narrower than the outwardly bent portions thereof.

2. In a band as claimed in claim 1, the links of the second row having extensions on their ends bent over to overlie partially said leg connecting parts, the recesses of the links provided with such extensions extending into the side walls of the links.

3. In a band as claimed in claim 2, all the links being of the same cross-section and cover plates on the links of such first row extending around the sides thereof,

whereby the links of the second row are spaced apart when the band is in contracted condition.

4. In a band as claimed in claim 1, the links of the second row having extensions on their ends bent over to overlie partially said leg connecting parts, said connecting parts having portions of different height, and said extensions overlying the portions of lower height, the recesses of the links provided with such extensions extending into the side walls of the links.

5. In a band as claimed in claim 4, all the links being of the same cross-section and cover plates on the links of such first row extending around the side thereof, whereby the links of the second row are spaced apart when the band is in contracted condition.

15 6. In a band as claimed in claim 5, the ends of the parts of the covers which overlie the outer walls being swaged over the ends of said parts.
